NAZAIRES DEMERS, OF LAWRENCE, MASSACHUSETTS.

SHUTTLE-BINDING MEANS.

Application filed January 9, 1925. Serial No. 1,475.

My present invention pertains to shuttle binding means; and it has for its general object to provide an improved shuttle binding means characterized by a yielding strip and possessed of the capacity of withstanding hard usage and of the ability to bring a shuttle gradually to rest without shock or injury and without liability of the shuttle rebounding.

10 Another object is the provision of shuttle binding means that is light in weight and inexpensive.

Another object is the provision of shuttle binding means adapted to be used on the 15 front or the back of shuttle boxes in different kinds of looms.

Other objects and practical advantages of the invention will be fully understood from the following description and claims when 20 the same are read in connection with the drawings, accompanying and forming part of this specification, in which:—

Figure 1 is a plan view showing one embodiment of my invention.

25 Figure 2 is a front elevation of the same.

Figure 3 is a plan view of one form of shuttle binder disassociated from the remainder of the shuttle box and slightly modified as compared with the binder in Figure 1.

30 Figure 4 is a plan view of a second modified binder.

Figure 5 is an elevation showing the inner surface of the binder shown in Figures 1 to 4.

35 Figures 6 and 7 are fragmentary detail sections on the lines 6—6 and 7—7, respectively, of Figure 1.

Figure 8 is a detail of the vertical spring arm, removed.

40 Figure 9 is a plan view showing a modification and with the shuttle out of the shuttle box.

Figure 10 is a front elevation of the modification shown in Figure 9.

45 Figure 11 is a detail view showing the mounting of the spring block.

Figure 12 is a detail perspective showing the rubber spring per se.

Figure 13 is a view taken at right angles 50 to Figure 11 and showing the means for guiding and holding the rubber spring.

Similar letters and numerals designate corresponding parts in all of the views of the drawings.

55 I illustrate in the drawings a portion of a lay A, together with the bottom race plate

B and the back C of a shuttle box, the said back being connected by bolts D and being detachable and adjustable. I also show a picker stick E movable in slot 2, Figure 9 and a picker 1, together with a shuttle 3 which in Figures 1 and 2 has fully entered the shuttle box.

A lug 4 projects from a pendent portion on the race plate B, and carries an upright stud 5 on which my shuttle binder generally designated by 6 is mounted to swing. The said binder 6 is detachably held in position by said stud, and the binder is prevented from rising on the stud by a washer secured 60 by a screw 7 on the upper end of the stud. A screw 8 bearing in the lug 4 is used to adjustably hold the stud 5 in position and is equipped with a lock nut 8*, the lug 4 being slotted at 4°, Figure 1.

Among other elements the binder 6 comprises a cast metal body in the form of a strip which is slotted at F for the admission of the weft or filling commonly used in looms. The said metallic strip is lined at 75 its inner side with two flexible strips 9 and 10, of leather, the said strips 9 and 10 being adapted to prevent contact of any part of the metallic shuttle. The meeting ends of the leather strips 9 and 10 are held in a notch 80 10* in the metallic binder body by a screw 11 screwed between the end portions of the strips. Consequently when either of the leather strips becomes worn it can be readily removed without affecting the other leather 85 strip and may as readily be replaced with a fresh leather strip. The metallic binder body has a portion 12 spaced, as designated by 9*, from that portion of the leather strip 10 that bears against the forward side of 90 the shuttle 3. Said portion 12 has a curved end apertured to receive a bolt 13 which also extends through coincident apertures in the lining strip 10 and an interposed spring plate 15, Figure 3, and is equipped with a 95 nut as shown. The strip 15 is not employed in the embodiment shown in Figures 1 and 2.

In the space 9* is a plate 16 which backs the leather strip 10 and is carried by two legs 17 guided and loosely movable in an aperture in the body portion 12. A web 22 extends between the legs 17, Figure 13, and rests in a kerf 21 in a rubber spring 20 to retain said spring between said legs, Figure 11. The said rubber spring 20 is backed by a screw 23 having a flat or disklike for-

ward portion and is also movable in said aperture in portion 12. The screw 23 bears in a laterally-projecting frame 19 on the binder portion 12 and is equipped with a lock nut 23*. Said frame 19 has connected at 19° a flat spring or spring strip 26. Manifestly when the shuttle contacts with the binder swell, the spring 26 will bear against the front of the lay A. That increases the pressure of the binder swell on the shuttle and assists in slowing down the shuttle. Then when the shuttle is near the end of the box or the picker 1, the shuttle shoulder contacts with the yielding strip 10, and the plate 16 moves against action of spring 20 and increases the pressure against the shuttle. In the modification of Figure 4, a flat spring 28 extends along behind strip 10 and strengthens the strip 10, and the spring 20 is used directly behind spring 28. Two holes are provided at 29, Figure 4, for the insertion of a pointed instrument through the medium of which the spring 28 can be moved toward the right to increase the pressure on the leather strip 10. The binder can be used with or without the spring 28 inasmuch as the rubber spring 20 can be regulated to exert the proper pressure against the plate 16 and leather strip 10 and enable the latter to operate to the best advantage. Obviously when the rubber spring 20 is impaired it can be readily removed and replaced with a fresh spring.

In the embodiments shown in Figures 3, 4, 9 and 10, the spring or spring strip 26 is secured by a unit as 23* on the screw 23 and against the outer end of the binder projection 19.

Adjustably connected at 31 to the sword 29* of the lay is a bracket 30 which is relatively arranged as illustrated. The said bracket carries a bolt 32 in an aperture 33 of the bracket, and a sleeve on the bolt 32 has a longitudinal slot 34, Figures 6 and 7, to receive the end portion of a coiled spring 35, said spring loosely surrounding said sleeve as will be readily understood. On the spring 35 is an upwardly reaching arm 37. The sleeve or bushing referred to is provided with an angular head 40 for the application of a wrench so that the coiled spring can be readily regulated as occasion demands. The arm 37 is provided with an angularly disposed portion at its upper end with rests in an eye 38 carried near the end of the binder body and prevents bearing of the binder on a lateral projection 39 on a plate 39* connected at 40° to the lay, so that no wear will take place on the binder. This provision is important inasmuch as the arm 37 serves to assure the shuttle properly entering the shuttle box without retardation of the shuttle but so that the shuttle is alongside the binder and flat on the race plate B as shown in Figure 2. As will be

understood from Figure 9 when the shuttle is not in the box the binder end occupies its normal position which is against the frame or plate 41 best shown in Figure 9.

The extent of movement of the binder is made clear by Figure 1, and it will be understood that when the binder is swung or forced outwardly by the shuttle entering the box, the arm 42 will be moved to turn the shaft 43, journaled at 44 in plate 39*, and lower the dagger so that in the beat up movement of the lay the dagger will not engage the stop member of the knock off mechanism. The binder is limited by the binder finger or protecting rod in well known manner. When the picker throws or picks the shuttle from the end of the box the pressure exerted by the strip 10 on the shuttle shoulder and on the binder swell releases at once. The shuttle moves along the back plate of the box and reed in line with the plate and straight through the shed and into the opposite box. The illustrated sloping of the strip 10 covers the shuttle filling groove and eye so as to prevent the thread from flashing away from the shuttle eye and groove which will result in breaking, kinking or slackening the thread.

As will be understood from Figure 5, I provide slots a^1 in the lining strips 9 and 10 the said slots being cut through the lining and allowing ample space for the thread to play. As illustrated the binder lining has a tongue which passes through the binder slot and is secured on the front of the binder at a^2 , Figures 1 and 2, this provision being made in order to prevent sidewise movement of the binder lining on the binder.

The binder 46, Figures 9 and 10, is made in a slightly different shape from the binder 6 so as to bring the point at which the lining 47 in Figures 9 and 10 can yield to a slightly different point. It will also be noticed that the binder stud 5 is differently positioned in Figures 9 and 10. The binder swell, however, is adapted to be swung outward at the point 47. This will be better understood when it is stated that the shuttle contacts or engages the yielding strip so that the outer end of the spring 26 will be swung toward the lay and will bear against the front of the lay. Manifestly this will assist in slowing down the shuttle and limiting the movement of the binder as is desirable. The binder 46 is further limited by the binder finger 42 in cooperation with a stop mounted on the shaft 43 so that when the shuttle engages or contacts with the yielding strip, the plate 16 behind the strip moves against the action of the rubber spring 20. Said spring 20 exerts its pressure on the lining 47 so that the pressure of the binder swell on the shuttle is reduced. The binder has an eye 38* to receive the angularly disposed portion of an arm 37 the lower end

of which is disposed in an eye 48 in the outer end of a bracket 30. At 49 is a thumb or guard above the eye 48 and relatively arranged to the arm 37 for controlling the arm, 5 the said arm 37 having a coil at 50 to facilitate in certain of its portions in the eyes 38 and 48 so that the arm can be removed from both eyes when necessary.

The spring 20 may be varied as to tension 10 by adjusting the screw 23 in the modification of Figure 4.

The spring 28 and plate 16 are not used together on the same binder, but the spring 23 can be used on all the binders.

15 The slot 14 in the strip 10 is to adjust or take up the strip—i. e., if when in use the strip becomes loose or spreads out so it can be taken up by the slot as represented in Figures 1 and 3. The binder can be used 20 with or without interposed spring plate 15. In the binder, Figure 4, the spring 28 is always used. The binder can rather be used without the spring 20 than the spring 28.

Having described my invention, what I 25 claim and desire to secure by Letters-Patent, is:

1. In shuttle binding means, a binder body having a space at its face, a flexible strip connected with the body and extending 30 across said space, and spring means carried by the body and backing the flexible strip in said space, said means including a spring strip adapted to bear against a lay.

2. In shuttle binding means, a pivotally 35 mounted binder body having a flexible facing extending at opposite sides of its center of movement and also having means exerting yielding pressure against said flexible facing at one side of said center of movement; the 40 said pressure exerting means including a spring strip adapted to bear against a lay.

3. Shuttle binding means comprising a 45 pivotally mounted binder body having a space at its face and at one side of its center of movement, a flexible facing carried by said body and extending across said space, and yielding means carried by the body and backing said facing in said space; said means including a spring strip adapted to bear 50 against a lay.

4. In shuttle binding means, a binder body having a curved end and a space at its face adjacent to said end, a flexible strip of leather carried by the body and extending across said space and connected to said curved end 55 of the body, and yielding means for exerting pressure against said strip in said space; the said means including a spring strip extending beyond the curved end of the binder body and adapted to bear against a lay. 60

5. In shuttle binding means, a pivotally mounted binder body having a notch and a space at its face and at one side of said notch, leather strips carried by the body at the face thereof and having end portions detachably secured in said notch, one of said strips extending across said space and detachably connected to the end portion of the body, and yielding means backing the last-named strip in the said space. 65

6. In shuttle binding means, a pivotally mounted binder body having a notch and a space at its face and at one side of said notch, leather strips carried by the body at the face thereof and having end portions detachably 70 secured in said notch, one of said strips extending across said space and detachably connected to the end portion of the body, and yielding means backing the last-named strip in the said space; the said binder body 75 and the said strips being apertured.

7. In shuttle binding means, the combination of a pivotally mounted binder body, said body having a space at its face and at one side of its center of movement, flexible 85 facing means carried by the body and extending across said space, means carried by the body for exerting yielding pressure against the flexible facing portion that extends across said space, and yielding means 90 connected with the inner end portion of the binder body.

8. The combination of a lay, a shuttle binder fulcrumed at an intermediate point of its length on the lay and having a spring-backed facing on one of its arms, and a spring strip carried by said arm and arranged to bear against the lay. 95

In testimony whereof I affix my signature.
NAZAIRE DEMERS.
